UNITED STATES PATENT OFFICE

126,376

DESIGN FOR A SERVICE BADGE OR SIMILAR ARTICLE

Margaret S. Casey and Mary E. Schuler,
Indianapolis, Ind.

Application January 18, 1941, Serial No. 98,184

Term of patent 7 years

To all whom it may concern:

Be it known that we, Margaret S. Casey and Mary E. Schuler, citizens of the United States and residents of Indianapolis, county of Marion and State of Indiana, have invented a new, original, and ornamental Design for a Service Badge or Similar Article, of which the following is a specification, reference being had to the accompanying drawing, forming part thereof.

In the drawing, Fig. 1 is a front elevational view of a service badge or similar article showing our new design; and

Fig. 2 is an edge view thereof.

We claim:

The ornamental design for a service badge or similar article, substantially as shown.

MARGARET S. CASEY.

MARY E. SCHULER.
